CLAIM

The ornamental design for wide track vacuum cleaner housing, as shown and described.

DESCRIPTION

FIG. 1 is a perspective view of a wide track vacuum cleaner housing showing my new design;

FIG. 2 is one side elevational view thereof;

FIG. 3 is a front elevational view thereof;

FIG. 4 is a top plan view thereof;

FIG. 5 is the other side elevational view thereof;

FIG. 6 is a rear elevational view thereof;

FIG. 7 is a bottom plan view thereof;

FIG. 8 is a perspective view of a second embodiment thereof;

FIG. 9 is a top plan view thereof;

FIG. 10 is one side elevational view thereof;

FIG. 11 is a front elevational view thereof;

FIG. 12 is another side elevational view thereof; and

FIG. 13 is a rear elevational view thereof.
